(57) **CLAIM**

The ornamental design for a rod bracket, as shown and described.

DESCRIPTION

FIG. 1 is a perspective view showing the new design for a rod bracket;

FIG. 2 is a front view thereof;

FIG. 3 is a rear view thereof;

FIG. 4 is a bottom view thereof;

FIG. 5 is a top view thereof;

FIG. 6 is a left side view thereof; and,

FIG. 7 is a right side view thereof;

The portions of the rod bracket in FIGS. 1-7 shown in broken lines are included to show features that form no part of the claimed design. In FIGS. 1-6, the dash-dot-dash lines represent boundaries of the claim.

1 Claim, 7 Drawing Sheets(56)
